United States Patent Office

Des. 212,399
Patented Oct. 8, 1968

212,399

REFRIGERATED DISPLAY STAND

Gene M. Kimler, 7269 Gail Way, Fair Oaks, Calif.
95608, and Stanley Paul Edwards, 1630 Kathleen
Ave., Sacramento, Calif. 95815

Filed Nov. 15, 1967, Ser. No. 9,423

Term of patent 14 years

(Cl. D30—11)

FIG. 4

FIG. 5

FIGURE 1 is a front perspective view of a refrigerated display stand, showing our new design;

FIGURE 2 is a side elevational view;

FIGURE 3 is a rear elevational view; the sign, a portion, and its support, have been omitted for convenience of illustration;

FIGURE 4 is a top plan view; and,

FIGURE 5 is a front elevational view.

We claim:

The ornamental design for a refrigerated display stand, as shown.
